POLYMER COATED SHEET MATERIAL

Howard L. Amberson, Madison, Wis., assignor to United States Rubber Company, New York, N.Y., a corporation of New Jersey

Filed May 24, 1961, Ser. No. 65,301

Term of patent 14 years

(Cl. D87—3)

I claim:

The ornamental design for a polymer coated sheet material, as shown.
